SELF-LOCKING CLOTHESLINE PULLEY

Frank J. Suter, Baltimore, Md.

Application August 9, 1939, Serial No. 289,316

2 Claims. (Cl. 188—65.1)

This invention refers to clamping devices for flexible cordage and more particularly to clothesline clamps, and the like.

The invention includes in its objects, the provision of a device that will tighten effectively on the cordage or rope run through it; that may be operated without handles or external mechanism; that may be used for holding cords of the clothesline type; and other similar uses, like that for supporting tennis nets, mooring boats, etc.; to have the device as simple as possible in construction and operation as to require little attention or operative skill. It also has among its objects to provide a system of clamping the cordage that will not injure same or place it under stress at any particular point. In addition, provision is made in the design that the device will automatically hold itself secure by the weight placed on the rope or cordage in its practical use.

Other objects will become apparent as the invention is more fully set forth.

The usual clothesline hanger with a pulley and a clamp that holds the cordage is in two separate elements. This causes the cordage to bind within the clamp independently of the pulley and to receive specific stresses at one particular location; to the general injury of the rope. In applicant's device the rope or line passes over the pulley that sustains its weight and load, and the clamp or clutch uses the pulley for a portion of its structure to bind the cordage within it. This not only eliminates the use of some parts in the device, but even makes it lighter since some of the material of the pulley is removed to make it form a ratchet gear.

The claw used on the ratchet gear is included close by, and readily switches into position for clamping and unclamping. The device itself consists of a skeleton frame in T-form, making it as light as possible without reducing its effectiveness.

The arrangement for holding the clamp in position when used as a clamp is very simple, and does not add to the weight or size of the device.

In the drawing which shows by way of example an embodiment of this invention:

Figure 1 is a side elevation of a clothesline clamp embodying this invention.

Figure 2 is a front view of Figure 1.

Figure 3 is a plan view of the device.

Figure 4 is a detail of the clutch arm used in the device, in perspective,

Figure 5 is a modified form of ring end for the clutch arm.

Similar reference characters refer to similar parts throughout the drawing.

In the construction of the device 1 represents

a bifurcated shank of a T-frame used for supporting the pulley 2, over which the line or rope 3 runs. The branches 4 of the frame are provided with thimbles 5, bevelled internally, and used for guiding the rope around the pulley. The pulley has a V-like shaped groove 6 arranged on its periphery, wide enough to allow the rope to ride easily within it. This groove is roughened as indicated to prevent the slipping of the rope and act as a brake therefor.

The walls 7, by the sides of the groove are formed with ratchet teeth 8, consisting of a straight face portion 9, a rounded peripheral portion 10, and a riding portion 11. The pulley is supported on a central pin or shaft 12 that is set in the shank portion 1. The shank is bifurcated to engage the pulley on both its side walls. A clutch arm 13, bent on a reversed curve has its tooth end portion 14 formed with a middle rounded portion or clutch 15 adapted to press on the rope passing over the pulley groove, without digging into same and injuring the fibres of the rope. The portions 16 on either side of the clutch are tapered and flattened at the end to engage with the ratchet teeth on either side of the pulley, and thus control its rotation in one direction. The clutch arm is pivoted on the shanks at 17, and has an extension eyelet or arm portion 18 projecting from the reversed portion, and with its hole 19 adapted for attachment to a hook or the like on a building or post. When secured to the hook, the weight on the rope pulls on the clamp, pivots the portion or arm 18, which is preferably underneath, and pulls it so that its tooth presses into the ratchet teeth and the clutch against the rope with its rounded cam portion. In the latter case the pressure increases as the pull on the arm 18 increases, and thereby forces it in more tightly into the groove 6. To tighten up on the rope, the rope is pulled on the loose end, the ratchet lifted to allow the pulley to rotate with it, and when tightened sufficiently, the arm 18 is pulled up to place the ratchet tooth and clutch in place, so the rope will not slip. The eyelet portion is then placed on the hook, and the pull, due to the weight, keeps the clutch and ratchet securely in place. The simplicity of the arrangement enables it to be used quickly and effectively without involving any appreciable trouble or effort.

The bottom of the groove 26 is knurled or roughened to form a firmer hold on the rope 2. In Figure 5, the end portion 18 of the clutch arm 13 is provided with a circular hole 29 therein, instead of the elliptical type indicated in other

views. In using the device, the rope that supports the weight or clothes is termed the snub or tension rope, while the other loose rope is termed the idler, and is pulled on, to bring the tension rope up tighter.

While but one form of the invention is shown in the drawing, it is not desired to limit this application in any way otherwise than limited by the prior art, as it is appreciated that other constructions can be made that would involve the same principles and come within the scope of the appended claims.

Having thus described the invention, what is claimed is:

15. 1. A device of the class described comprising in combination, a T-like frame having its shank portion bifurcated, a pulley having a peripheral groove formed thereon adapted to encompass rope or the like disposing therein and with the walls 20 about the groove adapted to form ratchet teeth, a pair of thimbles secured on the arms of said frame and aligned with said groove for the rope to pass therethrough after half looping the pulley, means for securing the pulley to the shank portion 25 and permitting same to revolve thereon, and a ratchet member loosely attached to the shank and formed to contact the tooth portions of the

pulley and the rope used in the pulley, said member having a lever arm with a ring thereon adapted to exert leverage on the portion in contact with the rope and teeth when the ring is supported and the looped rope is under tension 5 on the pulley.

2. A device of the class described comprising in combination a T-like frame; a pair of thimbles on the arms of the said frame, a pulley for rope or the like with a peripheral depression therein 10 with the walls of the lower portion of same adapted to give a wedge-like grip thereon and the upper portion formed into uniform projections extending above the proximate position of the rope bent around the pulley in the said depression 15 and passing tangentially to and through the said thimbles, a member for rotatively supporting the pulley on the frame, another member on the frame formed to fit against the projections and lock same with a clutch portion arranged for pressing the rope into the depression, said last mentioned member having means for supporting it and acting with leverage thereon in proportion to the tension on the rope looped around the pulley to snub the same.
